UNITED STATES PATENT OFFICE.

CARL HARTMANN, OF LANCASTER, NEW YORK, ASSIGNOR TO GOULD COUPLER COMPANY, A CORPORATION OF NEW YORK.

INTERRUPTER.

1,149,980.

Specification of Letters Patent. Patented Aug. 10, 1915.

Application filed June 11, 1913. Serial No. 773,011.

To all whom it may concern:

Be it known that I, CARL HARTMANN, a subject of the Emperor of Germany, and a resident of Lancaster, county of Erie and 5 State of New York, have invented certain new and useful Improvements in Interrupters, of which the following is a specification.

10 of which the following is a specification.
My invention relates to interrupters such
as are used in ignition systems in connection
with gas engines and the like.

The object of my invention is to provide an interrupter which is not only simple and efficient in operation and construction, but in which the contacts separate with a maximum velocity, whereby less arcing at the contacts and a hotter spark are obtained.

Further objects, features and advantages will more clearly appear from the detailed description given below taken in connection with the accompanying drawing, which shows a device embodying my improvements in one form.

Referring to the drawing, 1 represents a suitable fixed casing through which extends a rotating shaft 2 carrying rigidly therewith a cam 3 having two cam faces 4 and 5 thereon. Carried rigid with the casing 1 is a member 6 carrying binding posts 7 and 8. The member 6 also carries contacts 9 and 10 which are electrically connected to the binding posts 7 and 8 but otherwise insulated from the parts. Pivoted at 11 and 12 respectively, are two bell crank levers 13 and 14 carrying on one of their arms contacts 15 and 16, which are adapted to engage respectively, the contacts 9 and 10, between which the electrical circuits are interrupted. The frame 1 also carries a member 17 which has integrally formed thereon stationary guide members 18 and 19 having guide faces 20 and 21 respectively, substantially at an angle of 45° to the line drawn between the axes of the cam 3 and the guide rollers 25, respectively. The member 7 also carries stationary pins 22 and 23 upon which are loosely mounted rollers 24 and 25, respectively.

In operation the cam faces 4 and 5, as the shaft 2 rotates, are adapted to engage the rollers 24 and 25 and cause them to move up along the guides 18 and 19 to engage the upper ends 26 and 27 respectively, of the levers 13 and 14 to cause the levers to rock about their pivots and separate the contacts 9 and 15 and 10 and 16 respectively, in

opposition to the action of the springs 28 and 29. The parts are so arranged that a line drawn between the center of either of the rollers and the fulcrum of its corresponding lever passes substantially through the tangent point between the corresponding guide surface and the roller. In other words, the parts are so arranged that the direction of movement of the roller is substantially at right angles to the arm of the lever which the roller engages, or substantially parallel to the movement of that part of the lever member which the roller engages. In this manner the velocity of that part of the lever member which the roller engages, is substantially as great if not greater, than the velocity of the roller engaging the same. The distance between the contacts and the fulcrum of the levers is substantially equal to the distance between the point of engagement of the rollers with the levers and the fulcrum, so that long arms are avoided and the parts may be made small and light so as to have a minimum of inertia.

By the above arrangement a quicker break of the circuit between the contacts is obtained, whereby less arcing at the contacts and a hotter spark are produced, and still the moving parts have a minimum of inertia. Moreover, the arrangement shown and described forms a simple device in which two sets of interrupting contacts are provided, both operated from the same cam, whereby if one set fails the other set may be used, or the sets may be used for direct currents or alternating currents, respectively. 80 85 90

Although I have described my improvements in great detail and with respect to one particular embodiment thereof, nevertheless I do not desire to be limited to such details since many changes and modifications may well be made without departing from the spirit and scope of my invention in its broader aspects. 100

Having fully and clearly described my improvements, what I claim as new and desire to secure by Letters Patent is:

1. A device of the class described, having in combination relatively fixed and movable contacts, a spring maintaining said contacts normally closed, a lever fulcrumed intermediate its ends, the movable contact being carried on one end of said lever, a roller adapted to engage the other end of the lever, 119

a guide along which the roller is adapted to roll, and a cam engaging said roller to cause it to move the lever to separate the contacts.

2. The combination of the stationary 5 guide 18, the roller 24, the lever 13, the contacts 9 and 15, one carried by the lever 13, and the cam 3 for operating the roller along the surface of the guide to cause separation of the contacts, a line drawn between the 10 center of the roller and the fulcrum of the lever passing substantially through the tangent point between the guide surface and the roller.

3. The combination of two contacts, a lever 15 adapted to separate said contacts, a guide, a roller, and a cam adapted to engage the roller and operate it along the guide to engage and move the lever to separate the contacts, the direction of movement of the 20 roller being substantially at right angles to the arm of the lever which the roller engages.

4. The combination of two contacts, a member 25 for separating said contacts, a guide, a roller and a cam adapted to engage the roller and move it along the guide to engage the member and separate the contacts, the direction of movement of the roller being substantially parallel to the movement 30 of the member.

5. The combination of two sets of contacts, two members, one for separating each set of contacts, two rollers, a guide for each roller, and a cam operating both of said rollers to move them along the guides to move 35 the members to separate the contacts.

6. The combination of two sets of contacts, two members, one for separating each set of contacts, two rollers, a guide for each 40 roller, and a cam operating said rollers to move them along the guides to move the members to separate the contacts, the direction of movement of the rollers being substantially parallel to the movement of the 45 members at the respective points of engagement with the rollers.

7. The combination of two sets of contacts, two members, one for separating each set of contacts, two rollers, a guide for each 50 roller, and means operating said rollers to move them along the guides to move the members to separate the contacts, the direction of movement of the rollers being substantially parallel to the movement of the 55 members at the respective points of engagement with the rollers.

8. The combination of two contact-carrying lever members, springs operating on said lever members to maintain the lever members in normal position, a roller for 60 moving each lever member, a guide for each roller, and a single cam for engaging said rollers to move them along the guides and move the lever members, the direction of movement of the rollers being substantially 65 parallel to the movement of the members at the respective points of engagement with the rollers.

9. The combination of two contact-carrying lever members, two relatively fixed contacts coöperating respectively with the contact-carrying lever members, springs operating on said lever members to maintain the lever members in position with the respective contacts closed, a roller for moving each 70 lever member, a guide for each roller, and means for engaging said rollers to move them along the guides and move the lever members.

10. The combination of two contacts, a pivoted member carrying one contact, a roller adapted to engage said member to separate the contacts, a cam operating upon said roller to move the same, and a guide having a guiding surface at an angle to a line drawn between the axes of the cam and roller, the direction of movement of the roller being substantially parallel to the direction of movement of that part of the pivoted member engaged by the roller. 90

11. The combination of two contacts, a pivoted member carrying one contact, a roller adapted to engage said member to separate the contacts, a cam operating upon said roller to move the same, and a guide 95 having a guiding surface at an angle to a line drawn between the axes of the cam and roller, the direction of movement of the roller being substantially parallel to the direction of movement of that part of the pivoted member engaged by the roller, and the contacts being at substantially the same distance from the pivot point of the member as is the point of engagement of the roller with said member. 100

In testimony whereof, I have signed my name to this specification, in the presence of two subscribing witnesses.

CARL HARTMANN.
